UNITED STATES PATENT OFFICE.

FRANZ PAWLIK, OF RORSCHACH, AND KARL ALTHEER, OF HORN, SWITZERLAND, AS
SIGNORS TO JACOB SCHMIDHEINY, OF HIERBRUGG, ST. GALLEN, SWITZERLAND

THERMOSTATIC CIRCUIT CLOSER.

Application filed March 15, 1921. Serial No. 452,624.

To all whom it may concern:

Be it known that we, FRANZ PAWLIK, a citizen of the Republic of Czechoslovakia, and a resident of Rorschach, Switzerland, and KARL ALTHEER, a citizen of the Republic of Switzerland, and a resident of Horn a. Bodensee, Switzerland, have invented certain new and useful Improvements in Thermostatic Circuit Closers; and we do hereby declare the following to be a clear, full, and exact description of the invention, such as will enable others skilled in the art to which it appertains to make and use the same, reference being had to the accompanying drawing and to letters or figures of reference marked thereon, which form a part of this specification.

This invention relates to improvements in automatic temperature alarm devices and consists essentially in an electric contact device, comprising a contact cartridge which can be repeatedly used after giving an alarm by simply turning it upside down. Automatic temperature alarm devices are already known in which mercury or a fusible metal alloy is enclosed in a metallic cartridge or casing and is normally supported above a contact pin by a solidified insulating mass, which mass fuses upon an increase in temperature, whereby the mercury or alloy after the latter fuses is deprived of support and drops on the contact pin, thus closing the alarm device. Such devices have the disadvantage that a thin layer of the fusible insulating mass will remain on the metallic inner walls of the cartridge and will thus prevent making a reliable contact.

A construction according to this invention is illustrated by way of example in the accompanying drawing in which:

Fig. 1 is an elevation of an apparatus enclosing the device;

Fig. 2 a view of the interior of apparatus, the protective casing being in section;

Fig. 3 a longitudinal section of the contact cartridge,

Fig. 4 a cross-section on line A—B of Fig. 3,

Fig. 5 is a cross-section on line C—D of Fig. 2.

Fig. 6 illustrates a longitudinal section through a modified construction of a cartridge,

Fig. 7 is a cross-section along line E—F of Fig. 6 and

Fig. 8 is a longitudinal section of the construction illustrated in Fig. 5, the contact making parts being shown in a different operating position.

According to Fig. 3, the contact cartridge comprises a thin metal tube 5 closed in an air-tight manner at both ends by means of insulating plugs 3 and insulating cement masses 2. A contact pin 1 provided with a contact button and held in a central position, projects outwardly from the interior of the cartridge through each of the double plugs. The remaining inner space of the cartridge contains a solidified fusible mass 7 and a solid metal conductor, as the lead cylinder 4 resting on the latter; the said cylinder being centrally guided by means of three contact springs 6 secured to its circumference and sliding on the inner wall of the metal tube.

The mass 7 is so selected that it will fuse on a given upper temperature limit being reached in the medium surrounding the cartridge. In this way the lead cylinder is deprived of its solid support and owing to its weight drops on the contact button of the pin 1, the liquid being at the same time forced upwards.

As soon as the lead cylinder comes into contact with the contact button, the alarm circuit connected on the one hand to the metal tube and on the other hand to the button contact pin, will be closed, and an audible or visible indication may be given at any desired point. After melting, the mass will be situated above the lead cylinder. The cartridge can therefore be used again immediately after the solidification of the melting mass, by turning it upside down. For this reason it is easily possible to test the apparatus at any moment, and it remains ready for use for an unlimited time. In place of the lead cylinder 4 and of the insulating mass 7 there may be used only a fusible mass constituted by a metal alloy which, on melting, drops from a raised position and establishes contact.

The modified cartridge illustrated in Figs. 6—8 shows only one contact pin 1 provided with a contact button 9 and held in a central position by means of a plug 3 of an insulating cement mass by which the thin metal tube 5 is closed in an air-tight manner at one end, the other end of the tube 5 being closed by an integral cap. A circular groove 8 is pressed into the circumference of the tube 5

in order to retain the plug 3 in position. Metallic contact balls 10 are provided between the cylinder 4 and the button 9 of pin 1.

5 In Fig. 6 the solidified fusible mass 7 supports the cylinder 4 and the balls 10. When the mass 7 fuses the cylinder 4 and the balls drop, the latter rest on the button 9 and the cylinder 4 rests on the balls (Fig. 8). The 10 balls are pressed towards the wall of the tube 5 by the action of the conical ends of the cylinder 4 and of the button 9, whereby the alarm circuit, one of the conductors of which is connected to the metal tube and the other to the contact pin, is closed. In order to use the cartridge again, the latter is heated in the reversed position in which the pin 1 points upwards, whereupon the mass 7 fuses and the cylinder 4 and the balls 10 15 drop to the closed end of tube 5. After the solidification of the mass 7 the tube is turned upside down into the position shown in Fig. 6 in which it may be used again.

Figs. 1, 2 and 5 illustrate by way of example a construction of a portable contact apparatus which may be connected to a wall plug. To the insulating base *e* is secured in a depending position by means of a contact bracket *d* and clip *b* the above described contact cartridge *a*. The metal tube of the cartridge is in its turn electrically connected to the binding screw *i*₁, whilst the contact pin is connected by means of a contact spring *K* and wire *m* to the binding screw *i*₂. The screws *i*₁ and *i*₂ form a connection for the two conductors of the cable *c* provided with a plug at the end, which can be inserted into the alarm circuit. The inner part of the apparatus is protected by 20 a casing or sleeve constituted by two parts *g* and *f* screwed together at *h*.

By using a contact cartridge, the apparatus may be secured to a ceiling or to a wall, or any other holding device.

45 The apparatus is specially adapted for use as a fire alarm in combination with an electric alarm device for notifying danger of fire, or fire after it has already broken out. Moreover the apparatus in a suitable form

may be used to give warning when the highest admissible temperature is reached in warehouses of all kinds, and where there is danger of the temperature exceeding the limit in machine parts owing to heat generated by friction or on electric machine and apparatus etc.

As the device is comparatively inexpensive to manufacture it is possible to equip the rooms or the materials to be protected, with a large number of alarms in order to ensure 60 the desired degree of automatic supervision.

We claim:

1. An electric contact device for automatic temperature alarm devices, in combination, a cartridge consisting of a metallic tube 65 closed at one end, a fusible mass being an electric insulator melting at a predetermined temperature and enclosed in said tube, a metal body and metal balls arranged inside said tube and supported by said fusible mass 70 and deprived of their support on the mass becoming fused, and an insulated contact pin projecting through an air-tight closure provided at the other end of said tube into the interior of the latter and co-operating 75 with said metal balls and body.

2. An electric contact device for automatic temperature alarm devices, in combination, a cartridge consisting of a metallic tube closed at its upper end, a fusible mass 80 being an electric insulator melting at a predetermined temperature and enclosed in said tube, a metal body provided with a conically shaped lower end and metal balls below said metal body, arranged inside said tube and supported by said fusible mass and deprived of their support on the mass becoming fused, and an insulated contact pin provided with a conically shaped button 85 projecting through an air-tight closure provided at the lower end of said tube into the interior of the latter and cooperating with 90 said metal balls and body.

In testimony that we claim the foregoing as our invention, we have signed our names. 95

FRANZ PAWLIK.
KARL ALTHEER.
